DRAFT APPLIANCE

James L. Breese, Santa Fe, N. Mex., assignor to
Oil Devices, Santa Fe, N. Mex., a limited partnership of Illinois

Application March 9, 1940, Serial No. 323,057

8 Claims. (Cl. 126—290)

My invention relates to an improvement in means for starting pot type burners.

One purpose is the provision of an accessible inlet through which matches or other igniting means may be projected or inserted.

Another purpose is the provision of means for automatically closing the inlet after the match has been inserted.

Another purpose is the provision of means for automatically closing the aperture in response to increasing the heat of combustion in the pot.

Another purpose is the provision of means for providing an excess supply of air at the initiation of combustion.

Other purposes will appear from time to time in the course of the specification and claims.

I illustrate my invention more or less diagrammatically in the accompanying drawing wherein:

Fig. 1 illustrates a vertical axial section through a pot embodying one form of my invention;

Fig. 2 is a section on an enlarged scale along the line 2—2 of Fig. 1;

Fig. 3 is a front elevation on an enlarged scale of part of the structure shown in Figs. 1 and 2, illustrating the closure in open position;

Fig. 4 is a section on the line 4—4 of Fig. 3, illustrating the closure in both open and closed position;

Fig. 5 is a view similar to Fig. 4, illustrating the closing operation; and

Fig. 6 is a view similar to Figs. 4 and 5, of a variant form of the device.

Like parts are indicated by like symbols throughout the specification and drawing.

Referring to the drawing, I generally indicate any suitable pot wall, herein shown as generally cylindrical. It may be of sheet metal and is provided with a slightly concave bottom 2. 3 indicates any suitable oil inlet. 4 indicates a plurality of primary air inlets located at various levels. Secondary air supply may be admitted above the primary air holes, as by the upwardly tilted and more closely spaced secondary air inlets 5. It will be understood, of course, that the details of the burner do not of themselves form part of the present invention and are herein disclosed primarily for purpose of illustration.

I may employ also a pilot baffle 6, having a central aperture 7 adapted to divide the space within the pot into an upper and a lower chamber, the lower chamber being the combustion chamber for the pilot or low turndown stage of combustion. I preferably, but not necessarily, employ such a pilot baffle 6, and in such case find it preferable to provide a match or igniting

inlet 8 in the pot at a lower level than the pilot baffle 6.

In the form of Figs. 1 to 5 I illustrate as surrounding the pot aperture 8 an inlet passage 5 member having a roughly cylindrical portion 9 and a flange 10 abutting against the outer face of the pot and having, for example, ears 11, which may be bolted, spot welded, or otherwise secured to the outer face of the pot. It will be understood that little, if any, air leakage is permitted between the flange 10 and the opposed wall of the pot. An upper extension 12 of the flange 10 is employed, which may have outwardly extending ears 13, through which may pass any suitable pivoted pin 14, on which is pivoted a lid or closure member 15, having a finger or thumb engageable outward extension 16. It will be observed that when the lid 15 is in closed position, as in the full line disclosure in Fig. 4, it abuts against an inwardly extending flange 17, which defines the outer end of the cylindrical passage 9. Preferably this flange 17 is somewhat inclined from the vertical, as shown for example in Figs. 1, 4 and 5. The parts are so proportioned that a snug fit is obtained when the closure 15 falls or is moved to the full line position of Fig. 4. The inclined arrangement of the flange 17 insures that the closure will be carried by gravity to the closing position once it passes over center.

In order to provide an automatic movement of the member 15 to closed position, I provide a bimetallic strip or warping member having a portion 20, which may be spot welded or otherwise secured to the outer face of the closure 15. In order to obtain an increase in the length of this member and thus increase its flexure in response to heat, I may move it around the pin 14 as at 21, carrying its outer end 22 upwardly along and fairly snugly against the outside of the closure 15, as shown in the dotted line position in Fig. 4. When the burner is cold, the closure 15 may be raised by the finger to the dotted line position of Fig. 4, where, being over center, it will rest by gravity against the outer face of the pot 1.

It will be understood that the loop 21 is not sufficiently snug in its engagement with the pin 14 to prevent pivotal movement with the closure 15. In fact, it may be preferable to have no direct engagement at all. In any event, in the use of the device the operator merely lifts the member 15 to the dotted line position of Fig. 4 and then inserts a lighted match or any other suitable igniting means. The match serves as a species of temporary wick for vaporizing and lighting a

small amount of the fuel oil which lies in the concave bottom 2. As ignition is initiated and as the pot is heated, the warping bar 20, 21, 22 is subjected to this heat and the free end 22 of the warping bar moves it beyond the position in which it is shown in Fig. 5. As it warps or bends in response to the heat of combustion it very shortly tilts the closure 15 over center and permits it to fall by gravity to the full line position in which it is shown in Fig. 4.

The parts may be so proportioned that there is an initial delay during which an excess supply of air may flow in through the aperture 8. However, very shortly after the ignition of the fuel within the pot, increasing heat moves the closure 15 to closed position, and through the aperture 8 then passes no further air, and the holes 4 and 5 are properly proportioned to handle normal combustion conditions within the pot.

Fig. 6 illustrates a variant in which the aperture 8 may be closed by the bimetallic strip or warping bar 30, herein shown as secured to the exterior of the pot. The bar 30 is so proportioned that when the pot is cold it warps into the full line position in which it is shown in Fig. 6. This leaves the aperture 8 available for the introduction of a match or any other igniting means. In response to the heat of combustion the bar 30 warps to its normal dotted line or closed position, and no further air is thereafter admitted through the aperture 8.

It will be realized that whereas I have described and illustrated a practical and operative device, nevertheless many changes may be made in the size, shape, number and disposition of parts without departing from the spirit of my invention. I therefore wish my description and drawing to be taken as in a broad sense illustrative or diagrammatic, rather than as limiting me to my precise showing.

I claim:

1. In combination with a burner wall, an air inlet member in said wall, and an automatic closure therefor including a door hinged for rotation about a horizontal axis located above said inlet member, said door when in open position being gravitally supported over center, and heat responsive means for moving it over center and for thereby causing it to fall by gravity into closed position in relation to said inlet.

2. In combination with a burner wall, an air inlet member in said wall, and an automatic closure therefor including a door hinged for rotation about a horizontal axis located above said inlet member, said door when in open position being gravitally supported over center, and heat responsive means mounted on the door for moving it over center and for thereby causing it to fall by gravity into closed position in relation to said inlet to said inlet.

3. In combination with a burner wall, an air inlet member in said wall, and an automatic closure therefor including a door hinged for rotation about a horizontal axis located above said inlet member, said door when in open position being gravitally supported over center, and heat responsive means for moving it over center and for thereby causing it to fall by gravity into closed position in relation to said inlet including a bimetallic element interposed between a door and the burner wall.

4. In combination with a burner wall, an air inlet member in said wall, and an automatic closure therefor including a door hinged for

rotation about a horizontal axis located above said inlet member, said door when in open position being gravitally supported over center, and heat responsive means for moving it over center and for thereby causing it to fall by gravity into closed position in relation to said inlet including a bimetallic strip mounted on the door and interposed between the door and the burner wall.

5. A heat-responsive draft-regulating device for an air-admitting opening in an orchard heater, said draft-regulating device comprising: a draft-regulating plate adapted to be pivotally mounted adjacent said opening, said plate being movable between a first position affording relatively free passage of air through said opening and a second position restricting the passage of air through said opening, said plate in moving between said positions passing through an intermediate position, said plate being gravity biased toward said first position when it is between said first position and said intermediate position and being gravity biased toward said second position when it is between said intermediate position and said second position; and a bimetallic element operatively associated with said plate and disposed in heat-receiving relation to said heater and operable when heated to cause said plate to move from its first position to and through said intermediate position.

6. A heat-responsive draft-regulating device for an air-admitting opening in an orchard heater, said draft-regulating device comprising: a draft-regulating plate adapted to be pivotally mounted adjacent said opening, said plate being movable between a first position affording relatively free passage of air through said opening and a second position restricting the passage of air through said opening, said plate in moving between said positions passing through an intermediate position, said plate being gravity biased toward said first position when it is between said first position and said intermediate position and being gravity biased toward said second position when it is between said intermediate position and said second position; and a bimetallic element operatively associated with said plate and disposed in heat-receiving relation to said heater and operable when heated to move said plate against gravity from its first position to its intermediate position where it may fall freely with the aid of gravity to its second position.

7. A heat-responsive draft-regulating device for an air-admitting opening in a heater, said draft-regulating device comprising: a draft-regulating plate adapted to be pivotally mounted adjacent said opening, said plate being movable between a first position affording relatively free passage of air through said opening and a second position restricting the passage of air through said opening, said plate in moving between said positions passing through an intermediate position, said plate being gravity biased toward said first position when it is between said first position and said intermediate position and being gravity biased toward said second position when it is between said intermediate position and said second position; and a bimetallic element operatively associated with said plate and disposed in heat-receiving relation to said heater and operable when heated to cause said plate to move from its first position to and through said intermediate position.

8. A heat-responsive draft-regulating device for an air-admitting opening in a heater, said

draft-regulating device comprising: a draft-regulating plate adapted to be pivotally mounted adjacent said opening, said plate being movable between a first position affording relatively free passage of air through said opening and a second position restricting the passage of air through said opening, said plate in moving between said positions passing through an intermediate position, said plate being gravity biased toward said first position when it is between said 10 first position and said intermediate position and

5 being gravity biased toward said second position when it is between said intermediate position and said second position; and a bimetallic element operatively associated with said plate and disposed in heat-receiving relation to said heater and operable when heated to move said plate against gravity from its first position to its intermediate position where it may fall freely with the aid of gravity to its second position.

JAMES L. BREESE.
